PORTABLE CLEANING MACHINE

Application filed February 8, 1926. Serial No. 86,912.

This invention relates to a portable power operable cleaning machine.

The chief object of this invention is to clean and disinfect débris laden trays in a most expeditious manner through the use of a portable power operable cleaning machine.

The several features of the invention consist in the portability of the machine, the power operable mechanism for cleaning trays received by the machine, the tray handling mechanism, the disinfecting mechanism, the anchoring mechanism for the machine and the débris collecting and discharge mechanism.

The full nature of the invention will be understood from the accompanying drawings and the following description and claims:

In the drawings Fig. 1 is a perspective view of the entire machine showing several of the parts in open position to illustrate other parts. Fig. 2 is an end elevation of the invention. Fig. 3 is a longitudinal sectional view of the invention. Fig. 4 is a top plan view of the tray receiver with the clamping mechanism. Fig. 5 is a perspective view of the tray. Fig. 6 is an end view of a tray clamping mechanism in tray releasing position. Fig. 7 is a similar view of the same mechanism in the tray clamping position. Fig. 8 is a side elevational view of an operating mechanism for the clamping mechanism and is taken at right angles to Figs. 6 and 7. Fig. 9 is an elevational view of a modified form of the invention. Fig. 10 is a perspective view of the front end of the cleaner and of a modified form thereof.

In the drawings 10 indicates a framework, which unless otherwise specified, is substantially enclosed forming a compartment and which is supported by the wheels 11 and the caster wheels 12. A pair of toggle levers 13 are pivotally supported at one end at 14 on the framework and are connected at the other end by link 15 to a common plunger 16 connected by a link 17 to a lever handle 18 pivotally supported in the bracket 19. Each of the toggle levers 13 carries a connection 20 with a locking rod 21 that is slidably supported in the U-shaped brackets 22. Thus

when the handle is depressed, the plunger 16 is depressed which causes the locking rod 21 to engage the floor or earth and anchor the compartment vehicle against movement. Mounted on the top of the compartment is an electric motor 23 which herein is shown provided with a driving pinion 24 and a driving chain or belt 25 meshes with a gear 26 carried by shaft 27, the entire driving mechanism being externally positioned and exposed, but protected by the guard 28. A standard 29 has a hinge connection 30 permitting it to be knocked down for portability and clearance purposes, and said standard supports in swivel relation a pulley wheel 31 which is yieldingly and rotatably mounted and carries a suitable amount of cable 32, one end of which is connected to the motor 23 for energizing the same and the other end of which carries a fitting 33 for connection to the standard supply socket, whereby power for the motor is obtained from the usual wiring.

A suitable tray supporting framework comprises a pair of side members 35 connected together by the transverse portions 36, and the side members 35 are extended as at 37 and terminate in handles. The framework just described, shown most clearly in Figs. 3 and 4, is slidably supported in the guideways 38 and when the framework is seated in the compartment as shown in Fig. 1, said handles constitute a means for pushing and guiding the vehicle from place to place if desired.

Adjustably but rotatably mounted within the compartment in the supporting brackets 40 is a wire or steel bristle roller 41 which is self cleaning, and the same is mounted adjacent the aperture 42 through which the tray supporting framework 35-36 is slidably receivable. The entire compartment has an inclined face 43 and a pair of faces 44 and 45 which are connected together by the segmental portions 46. Said tiltable hopper thus formed is hingedly mounted at 47 in the frame and is receivable by the aperture 48. The latch 49 is adapted to maintain the aforesaid mechanism in closed relation with respect to the compartment.

whereby the hopper completely closes the same. Débris discharged by the brush collects by gravity in the tilttable hopper previously described, and when the hopper is tilted upwardly and outwardly, that portion which is collected on the bottom 45 is discharged on to the side near the bottom forming position, whereupon the same may be readily shoveled from the hopper. Substantially all of the débris is discharged into the hopper by reason of the inclined portion 43.

In Fig. 8 a modified form of the invention is illustrated and in this form of the invention the electric motor 123 includes a bevelled gear 124 which drives a shaft 125 terminating in a worm 125^a meshing with a worm wheel 126 on the shaft 127 mounting the roller or brush 41. A guard 128 is associated with the foregoing mechanism and protects the operator from the same.

The tray to be cleaned consists of a bottom 50, a pair of side walls 51 and an end wall 52. The tray supporting framework comprising the transverse elements 35 and 36, includes a plurality of spaced tray supporting members 53. The tray supporting framework previously described, is retracted as shown in Fig. 3, and positioned upon the same and locked thereon by the mechanism hereinafter described is the tray. Pressure upon the handles 37 following anchorage or locking of the vehicle into position, causes the tray to be passed beneath the brush and to be cleaned thereby, the excretion and débris being discharged into the hopper bottom previously described. In order to prevent fouling of the compartment and to simultaneously disinfect the tray, a hopper-like compartment 56 is provided having a corrugated roll 57 mounted in the discharge end thereof, and said roll 57 is driven by shaft 58 on which is mounted a pulley 59 driven by a belt 80 which is driven by a shaft 27, so that when the brush is rotated for cleaning, the corrugated roller 57 will be rotated to supply disinfectant in the form of crushed lime or lime powder to the tray, thus the lime and the débris and excretion will be brushed from the tray and collected by the hopper bottom of the compartment, thus preventing fouling of the contents of the compartment until such time as the same can be removed. Upon the return movement of the tray and the tray supporting mechanism the brush polishes the part previously cleaned and as the tray is withdrawn, a coating of lime or disinfectant material is deposited on the tray, keeping the tray disinfected as well as clean. The cages 55 for holding chickens and the like prior to shipment or dressing are each provided with a bottom tray to receive the waste products, and it is the tray which is removed in the cleaning process.

65 The means for locking the tray is as fol-

lows: the same being shown in Figs. 2 to 8 inclusive. In said figures there is illustrated a hand lever 60 pivotally mounted at 61 on one of the handles 37. This is in the form of a bell crank, in turn connected by a link 62 to a bell crank 63 pivotally mounted in a bracket 64 carried by the outermost transverse member 36. Bell crank 63 is connected by a link 65 to a lever 66 pivotally supported at 67 upon the member 36. The lever 66 includes an offset portion 68 which as shown by a comparison of Figs. 6 and 7, is adapted to clamp the edge 52 of the tray to the supporting framework slidably supported in the compartment. Another lever 166 having the same type of clamping extension 168 is pivotally supported at 167 and is connected by the link 165 to the link 66. A spring 70 has one end anchored to lever 166 and the other end suitably anchored to the framework such as 85 by or at pivot 67. Thus the spring 70 normally maintains the tray clamping mechanism in the released position and maintains the handle 60 in the elevated position. When it is desired to clamp the tray and operate 90 thereon, that is clean it and disinfect it, the handle 60 is depressed during the time that the tray supporting mechanism is projected into the compartment and withdrawn therefrom while supporting the tray.

In addition to the handles previously described, suitable handles 100 are also provided whereby the vehicle may be pulled as well as pushed from place to place. The tray supporting framework cannot be retracted 100 while the vehicle remains unanchored due to the position of lever 18.

In Fig. 10 the compartment is indicated generally by the numeral 110, the opening by the numeral 148, the closure by the numeral 144, the hinge mounting 147, the combination handle and lock by the numeral 149 and in this form of the invention the bottom of the container 145 is not connected to the closure 144, and therefore, is not tilttable with said closure. The hopper-like bottom previously described is nevertheless utilized so that when the closure 144 is released and lowered access is had to the compartment for removing the débris collected therein and by the hopper-like bottom.

The invention claimed is:

1. In a cleaning construction, the combination of a movable support, means for clamping an article to the support for movement therewith while cleaning, said means comprising a plurality of clamping levers, a manually operable lever for actuating the same, and yielding means for maintaining said clamping levers in one position, said manually operable lever being manually movable in opposition to said yielding means for moving the clamping levers into the opposite position.
2. A cleaning device having a frame, with

front opening therein for the insertion and removal of an article to be cleaned, means within said frame for cleaning such article, wheels on which the frame is mounted to render the device portable, anchorage means mounted on said frame so that when depressed it will engage the floor, ground and the like and hold the device stationary, and means mounted on the front of said frame and operatively connected with the anchorage means that obstructs said opening in the frame and prevents the insertion and removal of an article when the anchorage means does not engage the floor, ground and the like and will free said opening when the anchorage is in its downward locking position.

3. A cleaning device, substantially as set forth in claim 2, said anchorage means consisting of a pair of vertically movable bars, means on the frame for mounting each of said bars so that it will be movable vertically, substantially horizontally disposed levers pivoted at their ends to said frame and intermediate their ends to said anchorage bars, a vertically disposed bar pivoted to the inner end of said levers and mounted on said frame so as to be vertically movable, and a hand lever pivoted to the front of the frame in position to engage the upper end of said vertically movable bar and operate it, substantially as set forth.

4. A cleaning device having a frame, wheels for mounting the frame so that the device will be portable, anchorage means mounted on said frame and vertically movable to engage the floor, ground and the like for holding the device stationary, a platform movable into and out of the said frame through the front side thereof for supporting an article thereon while being cleaned, and means mounted on the front of the frame for operating said anchorage means, which, when the anchorage means is in its upper position, obstructs the movement of said platform when the anchorage means is in raised position, and, when the anchorage means is in its downward locking position permits the operation of said platform.

5. A cleaning device substantially as set forth in claim 4, said anchorage means consisting of a pair of rods, means on the frame for mounting said rods so that they are vertically movable, levers pivoted at their ends to said frame, and between their ends to said anchorage bars, a bar pivotally connected with the inner ends of said levers, and a hand lever pivoted to said frame immediately below the said platform and connected with the upper end of said last mentioned bar so that the hand lever will project into the path of the platform when the anchor rods are in their upper position and prevent operation of the platform, and will not be in the path of the platform when the anchor rods are down in holding position, whereby said plat-

form can be slipped in and out of the frame while the anchorage means holds the device stationary and cannot be slipped in or out of the same when the hand lever is in its upper position and the anchorage means elevated.

6. A cleaning machine having a frame, a horizontally disposed pan supporting member mounted in said frame so it will be slideable therein, adapted to support a pan with its inner end open, removable means on said supporting member for holding the pan thereon, a cleaning brush rotatably mounted on the frame above and in position to engage the pan for cleaning the same, and means for driving said brush so that the portion engaging the pan will sweep inwardly and discharge the contents of the pan through the open inner end thereof, and a receptacle in the frame for receiving said contents as it is discharged from the pan.

In witness whereof, we have hereunto affixed our signatures.
